UNITED STATES PATENT OFFICE.

NICHOLAS KING TURNBULL, OF MANCHESTER, ENGLAND.

GALVANIZING-BATH.

1,132,889.

Specification of Letters Patent. Patented Mar. 23, 1915.

Application filed November 13, 1913. Serial No. 800,720.

To all whom it may concern:

Be it known that I, NICHOLAS KING TURNBULL, subject of the King of Great Britain, residing at 3 York street, Manchester, in 5 the county of Lancaster, England, have invented new and useful Improvements in or Relating to Galvanizing-Baths, of which the following is a specification.

This invention relates to the galvanizing 10 of metal products such, for example, as wire or sheets, by immersion in molten zinc, and provides an improved construction or arrangement having for its object the prevention of the formation of "hard spelter" 15 from the iron sides of the bath. The improvements also enable economy in the quantity of zinc employed as well as protection of such zinc from undue oxidation at the surfaces, as hereinafter described.

20 Hitherto it has been usual to employ an iron or steel bath containing molten zinc, in some cases with considerable quantities of lead present. In other cases lining of the bath has been suggested, but unsuccessfully 25 applied; again, it has been proposed to arrange a certain amount of zinc (within an inner bath surrounded by lead) at the outgoing end only. Although many efforts have been put forward to produce a reliable 30 bath, little commercial progress has resulted.

The present invention embodies several 35 important details differing substantially from known efforts, whereby the zinc may cover the whole surface of the bath and yet receive no heat other than from the supporting metal such as lead.

The use of zinc at the outgoing end only 40 does not insure the best commercial finish to the products. The use of zinc over the whole surface of the bath prevents the otherwise ready oxidation of any zinc that may be floated to an uncovered surface of the lead. The product receiving an initial immersion 45 in zinc before entering the lead is insured of a better finish, particularly in the absence of "hard spelter."

By my invention, means are adopted to 50 prevent contact between the molten zinc and the iron sides of the bath, which contact is well known to set up a dissolving action resulting in the formation of "hard spelter."

In order that the said invention may be 55 fully understood, I will proceed to describe

the same with reference to the annexed 55 drawings, wherein—

Figure 1 represents a sectional elevation of a bath and setting provided in accordance with my improvements, while Figs. 2 and 3 are sections of parts exhibiting modifications hereinafter to be described.

a. is the metallic bath casing, which may be of iron or steel, and constructed according to known methods, but is preferably solid or welded.

b. is the setting therefor, and *c.* are the heating flues, passing along the end, sides and under surface of the bath, but not heating the bath where lined or chilled as hereinafter described. This lining, in the case 70 of Fig. 1, is provided by an interposed thickness of firebrick *d.*, or other material which has no action on the molten metal, which is contiguous to the bath sides, and is by preference rigidly attached thereto, as shown or 75 in any suitable manner.

In Fig. 2 the lining is furnished by providing means for chilling the metal immediately inside the bath to a temperature such that little or no detrimental action takes 80 place between the iron and the zinc. That is to say, instead of using fireclay, as in the former case, I cause the interposition of a thickness or layer of non-molten zinc. This chilling may be effected by means of a chamber *e.* formed in the setting, at the desired 85 level, through which air or water may be passed. Or the casing at these parts may be subjected to a spraying or other convenient application of cooling fluid, whether the 90 inclosed chamber be employed or not. Sufficient heat is imparted to the remainder of the bath to keep the metal or metals in the necessary molten condition, such heat being 95 conveyed to the zinc *f.* through the supporting body of lead *g.* or other metal having a higher specific gravity than zinc, and having little or no detrimental action on the bath.

The depths of the zinc at either end of the bath may be varied for the purpose of controlling the quantity of zinc and quality of 100 finish to be applied to the product.

Fig. 1 shows barriers *h.* inclosing a covering *j.* to prevent undue oxidation at the surfaces of the molten metal, and composed 105 of charcoal powder on the surface of the metal with a superimposed layer of sand; or it may be sand and charcoal mixed: the

layer of sand preventing the otherwise rapid oxidation of the charcoal.

In Fig. 3, an alternative arrangement is shown, the shield or cover *k*, being formed wholly of firebrick or other refractory material, the charcoal or other substance being dispensed with. This cover may be provided in sections or otherwise, and may be reinforced by an interior core or cores of metal if desired: also the same may project to any convenient depth, to economize the use of zinc, and special mixtures. I prefer to provide means for readily taking the end of the wire, sheet or strip through the bath, with the object of causing a minimum of disturbance to the surface, and the consequent prevention of zinc ashes. A device for this purpose is shown at *m*. in Fig. 1, and comprises a curved arm with hooked end, mounted upon a cross shaft *n*, in such manner as to describe a curve within the bath.

In use, the wire end is attached to the hook, and the arm is operated through suitable gearing such as *o*. This threading arm is preferably formed externally of material having no detrimental action upon the zinc, but may be reinforced by a metal core if desired. Assuming the metals of the bath to be in the molten state, the lever *m*, takes the wire *p*, under the guide *s*, to the outgoing end, where it is attached to the mechanism provided for coiling or otherwise receiving the galvanized product. With the threading arrangement described, the covered area of the bath is practically undisturbed under working conditions, and a large area of the bath may be so covered, the central isolated space *r*, shown in Figs. 1 and 3, facilitating the ready changing or insertion of guides such as *s*. This reduces the amount of zinc employed, and, where special mixtures or alloys are used in combination with the zinc,

considerably reduces the cost, at the same time giving a better control. Suitable substances are used in accordance with known practice at the entering and outlet ends, to insure satisfactory amalgamation and smooth surfaces: that is to say, by sand or wiping methods in the case of wire, and with the necessary fluxes in the case of sheets. In the drawings sand is indicated for this purpose by the letter *t*.

It is not essential in all cases for the flues *c* to be covered in at the top as shown: thus, the setting *b*, may be so formed that the said flues extend past the outer side of a coating of refractory material attached to the exterior of the bath casing *a*, and corresponding in position with the upper part of the setting shown herein. Other detail variations may be made without departing from the nature of the invention.

I claim:

A galvanizing bath comprising, in combination, an outer casing for the metal; a partial lining, composed of a compact non-corrosive material suitable for contact with molten zinc, and mounted closely against the inner face of the sides of said casing, said lining being restricted to the upper portion of said casing but otherwise substantially co-extensive therewith; and a setting for the bath provided with heating flues, said flues being adjacent to the exterior of the said casing at the lower and unlined portions thereof only, substantially as herein set forth.

In testimony whereof I have signed my name to this specification in the presence of two subscribing witnesses.

NICHOLAS KING TURNBULL.
